UNITED STATES PATENT OFFICE.

ORA E. MILLER, OF CEDAR RAPIDS, IOWA.

WINDOW BARRIER.

Application filed January 29, 1926. Serial No. 84,601.

This invention relates to window barriers for protection against burglary and theft, and the object of the invention is to provide a window with obstructive bars for the same, easily removable by the occupant of the house, and a connective bar for the upper sash whereby it may be let down any desired distance from the top, for ventilation of the apartment.

10 The invention is fully disclosed in the description and claims following, reference being had to the accompanying drawing, in which the device is clearly shown in a single view in perspective.

15 In the drawing, the numeral 5 denotes the jambs of a window casing 6, in which is mounted a pair of window sash, 7 being the lower, and 8 the upper. For sleeping apartments, especially, it is desirable to bar the 20 window against intruders, but to leave one or both of the sash ajar, to give fresh air to the apartment.

To one jamb is secured, as by screws 9, a wall-plate 10, pierced at 11 to admit the 25 ends of a series of cross-bars 12. To give a firm and stable bearing for the ends of the bars, the body portion of the wall-plate is offset, as shown. To the opposite jamb is similarly secured a wall-plate 13, which 30 is offset for the same reason, and is provided with open seats 14 to admit the opposite ends of the bars. This allows the easy insertion and withdrawal of the bars, as de-

sired. Hinged to the notched plate is a 35 companion plate 15, notched at 16 to coincide with the seats above mentioned. To fasten the bars in position the plate is turned up to vertical position, and locked fast to the stationary plate suitably, as by a padlock 17, the respective plates being provided 40 with holes 18 therefor. The grating thus formed serves as a barrier for the window, whether open or closed.

The upper sash is held in any desired 45 position by a single bar 19, which is secured at the upper end to the sash, and at its lower end has an eye 20 to receive any one of the cross-bars 12. It will be evident that the upper sash may be fastened open more or less, or fully closed, by first detaching the 50 desired bar from the grating, passing it through the eye of the strut-bar 19, and replacing the cross-bar in its respective wall-plate sockets.

Having thus described my invention, I 55 claim:

A window barrier, comprising a strut-bar attached to the upper sash, and formed at its lower end to receive a holding bar, and 60 a grating for the lower sash composed of 60 separately removable cross-bars, and wall-plates in which the bars are detachably secured, attached to the window frame.

In testimony whereof I affix my signature.

ORA E. MILLER,
